(57) **CLAIM**

The ornamental design for a spacer for helmet-mounted accessories, as shown and described.

DESCRIPTION

FIG. 1 is a perspective view of a spacer for helmet-mounted accessories showing our new design.

FIG. 2 is a front orthographic view thereof;

FIG. 3 is a rear orthographic view thereof;

FIG. 4 is a right side view thereof;

FIG. 5 is a left side view thereof;

FIG. 6 is a top view thereof; and,

FIG. 7 is a bottom view thereof.

The broken lines shown in FIGS. 1–7 are included for the purpose of illustrating environmental elements only and form no part of the claimed design.
